(57) **CLAIM**

The ornamental design for a suspension component as shown and described.

DESCRIPTION

FIG. 1 is a perspective view taken from a front, left side of a suspension component according to my design; FIG. 2 is a perspective view taken from a rear, right side thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a perspective view taken from a front, left side of a suspension component according to another embodiment of my design;

FIG. 10 is a perspective view taken from a rear, right side thereof;

FIG. 11 is a left side elevation view thereof;

FIG. 12 is a right side elevation view thereof;

FIG. 13 is a front elevation view thereof;

FIG. 14 is a rear elevation view thereof;

FIG. 15 is a top plan view thereof;

FIG. 16 is a bottom plan view thereof;

FIG. 17 is a perspective view taken from a front, left side of a suspension component according to another embodiment of my design;

FIG. 18 is a perspective view taken from a rear, right side thereof;

FIG. 19 is a left side elevation view thereof;

FIG. 20 is a right side elevation view thereof;

FIG. 21 is a front elevation view thereof;

FIG. 22 is a rear elevation view thereof;

FIG. 23 is a top plan view thereof;

FIG. 24 is a bottom plan view thereof;

FIG. 25 is a perspective view taken from a front, left side of a suspension component according to another embodiment of my design;

(Continued)

FIG. 26 is a perspective view taken from a rear, right side thereof; (56)

FIG. 27 is a left side elevation view thereof;

FIG. 28 is a right side elevation view thereof;

FIG. 29 is a front elevation view thereof;

FIG. 30 is a rear elevation view thereof;

FIG. 31 is a top plan view thereof; and,

FIG. 32 is a bottom plan view thereof.

In the drawings, the broken lines depict portions of the suspension component that form no part of the claimed design.

1 Claim, 32 Drawing Sheets
